UNITED STATES PATENT OFFICE.

FREDERICK FICKEY, JR., OF BALTIMORE, MARYLAND, ASSIGNOR TO
WILLIAM H. FICKEY, OF SAME PLACE.

IMPROVEMENT IN TOBACCO-PIPES.

Specification forming part of Letters Patent No. 40,536, dated November 3, 1863.

To all whom it may concern:

Be it known that I, FREDERICK FICKEY, Jr., of the city of Baltimore, in the State of Maryland, have invented a new and Improved Tobacco-Pipe; and I do hereby declare the following to be a full and correct description of the same, reference being had to the accompanying drawings, in which—

Figure 1 is a vertical section from front to rear of the pipe-bowl on the line *y* *y* of Fig. 3. Fig. 2 is a transverse vertical section of the same on the line *z* *z* of Fig. 3. Fig. 3 is a horizontal section through the lines *xx* of Figs. 1 and 2. Fig. 4 is a side elevation of the pipe-bowl in a position corresponding to that of the section Fig. 1. Fig. 5 is a front elevation of the same corresponding in position with the section Fig. 2.

The same part is marked by the same letter of reference wherever it occurs.

The nature of my invention consists in such an arrangement of the smoke-passages of a tobacco-pipe that the saliva and nicotine, respectively, will be received and retained in separate receptacles and prevented from mingling together or being drawn back into and through the pipe-stem, all substantially as hereinafter more particularly described.

The great desideratum of the tobacco-smoker is to receive the smoke into the mouth in a cool and dry state and free from nicotine or saliva or a mixture of the two. In pipes of the ordinary form the saliva from the mouth descends the stem and mingles with the nicotine, which collects in the bottom of the bowl, and when a sufficient quantity of these fluids has accumulated to be affected by the suction they are drawn together through the stem into the mouth, producing a bitter, acrid, and highly disagreeable taste, and having a tendency to excoriate the mucous membrane of the mouth and lips. The object of my invention is to remove this difficulty.

To enable others to make use of my invention, I will proceed to describe the construction and operation of my improved pipe, referring to the drawings which are made part of this specification, in which—

A marks the bowl of the pipe in which the tobacco is placed. The bowl A is connected

by passage *a* with a larger upright passage, B. This passage B is open at its lower end, where it has a projecting screw-thread, onto which the nicotine-cup D is screwed, as shown in Fig. 2. The upper end of tube B communicates by a horizontal passage, *b*, with the upright passage C, the lower end of which communicates by passage *c* with the smoke-chamber above the saliva-cup E. This chamber opens into the pipe-stem through passage *d*.

F marks the socket which receives the pipe-stem. The upper end of passage C is open, and receives a screw-cap, *e*, which can be removed, in order to cleanse the passage.

The operation is as follows: The pipe being filled and lighted, the smoke is drawn from the bowl through passage *a* into the upright passage B. This passage will necessarily receive the nicotine, which will fall to the bottom and be collected in the cup D, while the smoke passes up the passage B, through passage *b*, into and down passage C, through passage *c*, over the saliva-cup E, into passage *d*, and thence into the pipe-stem and the mouth of the smoker. Any saliva that may descend the pipe-stem will be received and retained in the cup E, which is screwed or in other convenient manner attached to the bottom of the pipe in the position shown in the drawings. The cups D and F can be unscrewed and emptied as often as may be required.

It will be observed that the nicotine cannot pass into the saliva-cup, as it is compelled by gravity to fall into the cup D. The saliva-cup also being below the line of draft its contents will not be subjected to suction, and hence will not be drawn into the pipe-stem. Thus the smoke will be received pure and dry into the mouth.

When the cups D and E and the cap *e* are removed, the pipe can be readily cleansed, owing to the easy access afforded through the open ends of the passages B and C.

Having thus fully described my invention, what I desire to claim, and secure by Letters Patent, is—

So arranging the smoke-passages of a tobacco-pipe, in combination with distinct receptacles for nicotine and saliva, that these

fluids respectively will be received and retained in separate vessels and be prevented from mingling together or being drawn into and through the pipe-stem, the arrangement and construction being substantially as described and represented.

The above specification of my said inven-

tion signed and witnessed at Washington, this 23d day of March, A. D. 1863.

FRED. FICKLEY, JR.
